UNITED STATES PATENT OFFICE

150,398

DESIGN FOR A FRUIT JUICER

Drake Bergen and David Cohl, Chicago, Ill.

Application January 6, 1947, Serial No. 135,970

Term of patent 3½ years

(Cl. D89—1)

To all whom it may concern:

Be it known that we, Drake Bergen and David Cohl, citizens of the United States, residing at Chicago, in the county of Cook and State of Illinois, have invented a new, original, and ornamental Design for a Fruit Juicer, of which the following is a specification, reference being had to the accompanying drawing, forming part thereof.

Fig. 1 is a front elevational view of a fruit juicer, showing our new design;

Fig. 2 is a side elevational view, partly broken away; and

Fig. 3 is a top plan view.

We claim:

The ornamental design for a fruit juicer, as shown.

DRAKE BERGEN.
DAVID COHL.
